UNITED STATES PATENT OFFICE.

DAVID H. CLARK AND RUFUS J. MORTON, OF GREENSBORO, NORTH CAROLINA; SAID CLARK ASSIGNOR TO SAID MORTON.

PICKER MECHANISM FOR LOOMS.

1,087,082.

Specification of Letters Patent. Patented Feb. 10, 1914.

Application filed April 21, 1913. Serial No. 762,597.

To all whom it may concern:

Be it known that we, DAVID H. CLARK and RUFUS J. MORTON, citizens of the United States, residing at Greensboro, in the county 5 of Guilford, State of North Carolina, have invented a new and useful Picker Mechanism for Looms, of which the following is a specification.

The present invention relates to improvements in picker mechanisms for looms, one 10 object of the invention being to provide a picker mechanism which will impart a straight throw or impulse to the shuttle, and to so construct the mechanism that the 15 shuttle is received by a spring cushion at the end of its movement, the present mechanism dispensing with the ordinary picker stick and simplifying the structure of the same, the picker mechanism being bodily 20 carried in the lay beam of the loom.

A further object of the present invention is the provision of a novel form of picker mechanism in which a single spring is connected to two picker slides, there being an 25 operating and releasing mechanism, whereby the propelling slide is locked and due to the pressure exerted upon the opposite slide during the release of the propelling slide, receives sufficient force, from the spring to 30 propel the same and the shuttle, the receiving slide which when receiving the shuttle preventing any undue jar.

With the foregoing and other objects in view which will appear as the description 35 proceeds, the invention resides in the combination and arrangement of parts and in the details of construction hereinafter described and claimed, it being understood, that changes in the precise embodiment of 40 the invention herein disclosed can be made within the scope of what is claimed without departing from the spirit of the invention.

In the drawings—Figure 1 is a longitudinal sectional view through the lay beam 45 with the parts in the position they assume after having propelled the shuttle from the left toward the right and during the setting and locking of the picker slide at the right. Fig. 2 is a similar view with the parts in the 50 position they assume just prior to the setting and locking of the picker slide at the left and the placing of the picker slide at the right under tension previous to the release thereof. Fig. 3 is a top plan view of the lay beam, with the upper plate removed at the right hand side with the picker slide in the

position as shown in Fig. 2. Fig. 4 is a section taken on line 4—4 of Fig. 1.

Referring to the drawings, the lay beam, which may be taken indicative of the usual form of lay beam used with looms, is composed of two longitudinal strips or plates 1—1', which are held in spaced relation to each other by means of the blocks 2 at the respective ends thereof, to provide the longitudinal mechanism receiving space 3 therebetween.

The present beam is designed to be what is known as the legless type and to slide upon the rods 4 in its necessary movement 70 within the loom.

Fitting upon the upper face of the lay beam and concealing a greater portion of the space 3, is a sheet 5, preferably of metal and which constitutes the surface upon 75 which the shuttle is moved longitudinally of the lay beam, said sheet 5 at opposite ends being provided with the longitudinal slots 6—6', through which are adapted to project the two picker slides 16, the detail construction and operation of which will be set forth later on.

Connected across the space 3 at the under side of the plates 1—1', and adjacent the center thereof, as clearly shown in Fig. 1, 85 are two straps or plates 7, which hold the operating bar 8 properly positioned within the space 3 and against downward displacement, and thus provide a means whereby the operating bar 8 is bodily carried by the 90 lay beam. In order to impart the desired reciprocatory movement to the operating bar 8, a lug 9 is connected thereto and depends from the under side thereof between the straps or plates 7, and has operably connected thereto, an arm 10, which may be taken indicative of a portion of the loom and is the means whereby the picker slides 16 are properly operated due to the reciprocation of the operating bar 8.

The opposite ends 11 of the operating bar 8 are in a plane above the intermediate recessed portion thereof formed by the two shouldered portions 13, which constitute a means for limiting the respective inward 105 movements of the operating bar 8, and, as will also presently appear, a means for releasing the picker slides 16, while the extreme ends 12 thereof are disposed to disengage and be engaged by the lower projecting ends 18 of the respective picker slides 16.

In order to provide for a straight line

movement in both of the picker slides 16, the oppositely disposed recessed portions 14 are formed in the plates 1--1' at each end thereof and receive the guiding member 15 of each picker slide 16, the upper end of each picker slide being provided with the buffers 17 for engagement with the respective ends of the shuttle S, as clearly shown in Fig. 1.

10 The inner end of each guiding member 15 is provided with the two spaced apertured lugs 19, between which is adapted to fit the apertured lug 20, a pin 21 being provided to form a hinging connection thereto so that 15 the flexing member 22 may be properly connected to the guiding member 15 of each picker slide.

10 The respective flexing members 22 of each picker slide are disposed for vertical swinging movement within the space 3 and project toward each other, as clearly illustrated, 20 the respective bails 23 being pivotally connected at their inner ends and forming a connecting medium for the single spring 24, 25 which forms a resilient operating connection between the two picker slides and a means whereby the propelling slide is given the proper impulse to throw the shuttle S to the receiving slide which is thus cushioned, the slides alternately being the propelling and receiving slides during the loom 30 operation.

10 The flexing member 22 is provided with the lower shouldered portion 25, and the 35 inclined lower face 26, so that when the members are in the position as shown in Fig. 2, the operating bar 8 being moved from right to left so that the slide 16 at the left is being moved to place tension upon the 40 spring 24, the shoulder 25 of the flexing member 22 of the slide at the right is placed in engagement with the holding pin 27. Thus the shoulder 13 of the bar 8 at the right will gradually ride upon the cam face 26 of the flexing member at the right and elevate the shoulder 25 and release it from the pin 27, so that by the time the slide at 45 the right has been moved to its full left position, and the spring 24 has been placed 50 under its greatest tension, the slide 16 at the right thus relieved, will be propelled suddenly and assume its farther inmost position and give the necessary impulse to the shuttle to throw the same across the lay 55 beam to be cushioned by the slide 16 at the left which has been placed in such a position that its shoulder 25 of its flexing member is slightly beyond its pin 27 and thus is in a loose condition so that when the shuttle 60 strikes the same, the spring 24 will act as a cushion and relieve the strain thereupon.

10 It will be noted that when the parts are 65 in intermediate position, that is after the shuttle has been received by one slide and

properly cushioned, that both pins 27 are in spaced relation to the respective shoulders 25 of both flexing members 22, and therefore the slide 16 which has just propelled the shuttle, has a slight movement away 70 from the center of the beam before the shoulder 25, all as clearly illustrated at the right in Fig. 1, has engaged the pin 27, the spring 24 being placed under initial tension during the movement of the bar 8 as for instance 75 to the left as viewed in Fig. 1 until the slide 16 at the left has assumed the position at the left as shown in Fig. 2, at which time the spring is being placed under tension such tension continuing until the shoulder 13 releases the shoulder 25 as previously described.

10 By mounting the guiding members 15 as shown, a straight line movement is imparted to the slides 16, so that the shuttle receiving 85 buffers 17 are always in the desired line, while with the flexing members 22, constructed as shown, in combination with the operating bar 8, the respective picker slides are set, locked and released automatically to 90 alternately operate as propelling means and also as receiving and cushioning means, the single spring 24 operating to perform both functions, so that the least perceptible jar is caused to the picker slides when receiving 95 the propelled shuttle.

10 What is claimed is:

1. A picker mechanism for looms, including a lay beam, two picker slides mounted for limited sliding movement at the respective ends thereof, a flexing member carried by each picker slide within the lay beam, a resilient connection between both flexing members of the slides, an operating bar mounted for reciprocation within the lay beam, and coöperative means carried by each end of the operating bar and the picker slide and flexing member, whereby during the reciprocation of the operating bar, and during the setting of one slide, the resilient connection is placed under tension and the opposite slide is released.

10 2. A picker mechanism for looms, including a lay beam, two picker slides mounted for limited sliding movement in the respective ends thereof, a flexing member connected to each slide within the lay beam, a spring connecting both flexing members within the lay beam, an operating bar mounted for reciprocation within the lay beam, and coöperative means carried by each end of the operating bar and the picker slide and flexing member, whereby during the reciprocation of the operating bar, and during the setting of one slide, the spring is placed under tension and the opposite slide is released.

10 3. A picker mechanism for looms, including a lay beam provided with a longitudinal channel in the under surface thereof, two 130

picker slides one at each end of the lay beam, each disposed for limited longitudinal movement within the channel thereof, two flexing members, one pivoted to each picker 5 slide within the channel, each of said flexing members being provided with a locking shoulder and a cam face, a spring connecting the adjacent ends of each flexing member, an operating bar mounted within the 10 channel of the lay beam for reciprocatory movement, and means carried upon each end of the locking bar for engagement with its respective picker slide and flexing member, whereby during the setting of one picker

slide, the spring is placed under tension and 15 the opposite slide locked, the continued movement of the operating bar releasing the locked slide to the tension of the spring and permitting the other slide limited movement to receive and cushion the propelled shuttle. 20

In testimony that we claim the foregoing as our own, we have hereto affixed our signatures in the presence of two witnesses.
